FISHING LURE

Earl Robinson and Paul P. Walraven, Atlanta, Ga.

Application July 16, 1956, Serial No. 42,259

Term of patent 14 years

(Cl. D31—4)

FIG. 1.

FIG. 2.

FIG. 3.

Figure 1 is a side elevational view of a fishing lure, showing our new design.

Figure 2 is a top plan view, the front hook being omitted for clarity of illustration.

Figure 3 is a front elevational view, the rear hook being omitted.

The dominant features of our design reside in the full line portion of the drawing.

We claim:

The ornamental design for fishing lure, substantially as shown and described.
